THERMOSTATIC UNIT

John E. Woods, Brookline, Mass., assignor to
Clifford Manufacturing Co., Boston, Mass., a
corporation of Delaware

Application June 4, 1940, Serial No. 338,747

1 Claim. (Cl. 297—8)

The present invention relates to improvements in thermostatic units, and is more particularly concerned with improvements in such units which embody a sealed-in actuator and attached capillary for remote control.

The object of the invention is to improve and reorganize such units for the purpose of increasing the reliability and ruggedness as handled in the ordinary application, and with the above and other objects in view, the various features of the invention consist in certain novel features of construction, combinations and arrangements of parts hereinafter described and claimed, the advantages of which will be obvious to those skilled in the art from the following description.

In the accompanying drawing illustrating the preferred form of the invention, Fig. 1 represents a bottom plan view of the unit; and Fig. 2 is a section in elevation of the unit before insertion of the capillary.

Upon inspection of the drawing, it will be observed that the unit generally comprises a cup-shaped housing 10 having an integral bottom portion 12 which may be ribbed or embossed at 14 to strengthen the bottom and prevent distortion. The bottom portion is also provided at one side of the center with an inwardly directed opening 16 having an integral neck 18 for the reception of the end of a capillary. A capillary in the form of a tube 20 of appropriate diameter is provided with an end portion 22 turned at right angles to its length and fitted within the necked opening 16 and sealed or bonded thereto by solder 24 as indicated. The lengthwise portion of the capillary contacts with and lies against the flat bottom portion extending from the opening diametrically across the bottom to an external point beyond the margin.

The length of the capillary is positioned and reinforced by a clip 25, which as shown in Fig. 2 may take the form of a raised bridge or guiding portion 27 formed integral with two anchoring legs 29. These legs engage with and are bonded to the bottom of the cup preferably by spot welding, and the raised bridge portion affords sufficient space therebetween and the bottom of the cup for the passage of the capillary tubing. The opening 30 presented by the bridge faces the opening in the cup bottom and is generally aligned with the longitudinal axis of the capillary which passes therethrough. There may be a slight clearance between the capillary and bridge when in position to permit insertion of the capillary after the bridge has been secured to the cup bottom.

With this construction the strain of the bending movements to which the capillary is inevitably subjected in use is sustained largely by the bridge, and little or no strain is imposed upon the solder joint at the point where the inturned

end of the capillary is sealed to the cup bottom. By spacing the bridge and opening 16 upon the same diameter at opposite sides of the center, a substantial length of the capillary is supported in comparison with the diameter of the cup, and a superior resistance is obtained as compared with the support of the capillary in close proximity to its entering point.

The cup-shaped housing encloses an operating 10 diaphragm which is sealed therein and is subject to the fluctuations in pressure introduced into the interior 32 of the housing through the capillary. This diaphragm may be of the form indicated in Fig. 2 in which a dished head portion 34 forms part of a two-fold bellows wall 36 provided with an enlarged fold 38 which is bonded to the wall of the cup-shaped housing and serves to anchor the diaphragm in position. Subject to fluctuations of pressure within 15 the space 32, the movable wall 34 is raised and lowered to control an external operating member.

As indicated again in Fig. 2, the entire assembly within the housing is enclosed by a disk-like cover 40 bonded at its outer periphery to the housing at 42, the edge of the cover, as shown, seating within a recess 44 formed in the wall of the housing. The interior of the cover is provided with a central opening 46, which rests upon the head of the diaphragm and limits outward movement, a sealing disk 48 being interposed therebetween to seal the interior of the diaphragm in the outward position. Attached to the movable head 34 may be a U-shaped bracket 20 25 30 35 50 55 50 which projects beyond the cover and serves as a connection for operating any appropriate instrumentality such as a switch.

What is claimed is:

A thermostatic unit comprising a movable diaphragm, a cup-shaped housing of drawn metal enclosing the diaphragm, the housing including an integral bottom provided with a recessed portion having formed therein an inwardly extending necked opening of smaller diameter than the recess, a length of capillary tubing having an end portion turned angularly with respect to its length and received within the necked opening, the portion of the capillary in the vicinity of the turn being free of the recessed portion of the housing to permit a continuous circular bond by soldering or the like between capillary and housing around the necked opening, the length of capillary lying in juxtaposition to the bottom portion of the cup and extending outwardly beyond the margin, and means for anchoring the capillary to the bottom of the housing at a point remote from the point of connection adjacent the necked opening, said anchoring means comprising a clip bridging the capillary and secured to the bottom of the housing.

JOHN E. WOODS.
